Inventor,

N.H. Paige

United States Patent Office.

W. H. PAIGE, OF SPRINGFIELD, MASSACHUSETTS, ASSIGNOR TO HIMSELF, JOHN SWEENEY, AND JAMES W. RUSSELL, OF SAME PLACE.

Letters Patent No. 83,536, dated October 27, 1868.

IMPROVED SEAT-BACK.

The Schedule referred to in these Letters Patent and making part of the same.

To all whom it may concern:

Be it known that I, W. H. PAIGE, of Springfield, in the county of Hampden, and State of Massachusetts, have invented a new and useful Improved Seat-Back; and I do hereby declare that the following is a full, clear, and exact description thereof, reference being had to the accompanying drawings, making a part of this specification, and to the letters of reference marked thereon, in which—

Figure 1 is a front view of a seat-back, with my invention applied;

Figure 2 is a vertical transverse section, through line B C of fig. 1;

Figure 3 is an end view of the wood or frame of a seat-back, showing the bearings for springs;

Figure 4 is a side and front view of a spring;

Figure 5 is a back view of a portion of a seat-back, with the springs applied;

Figure 6 is a front view of the same;

Figure 7 is a vertical transverse section, through a portion of the seat-back, showing details of construction of one modification of my invention; and

Figure 8 is a front view of a portion of the frame, showing the same modification.

My invention relates more particularly to the elastic portion of a seat-back, and it consists in such construction of the same whereby the back will conform more perfectly to the back of the person using it, than other seat-backs now in use, while it still retains all the elastic features of a seat constructed with especial regard to ease and comfort.

As seat-backs are now constructed, a large portion of the back yields to the pressure of the person using it, so that it does not adapt itself to the body of the user, merely possessing an elastic principle, without any particular adaptation to the form of the body pressing upon it.

To remedy this defect, I use straight, flat metallic springs, so arranged that each end bears against a solid or firm bearing, being curved when in place.

That others skilled in the art may be able to make and use my invention, I will proceed to describe its construction and application to use.

In the drawings—

A represents the foundation or frame of a seat-back, which may be a solid piece, or framed, or it may be shaped properly, and have portions removed, to make the back as light as possible, as shown in figs. 5 and 6, and along the edge of such frame, both at the upper and lower sides, is made the channel *n*, or a longitudinal strip, *m*, as shown in figs. 7 and 8, may be either glued or secured to the frame or back by means of screws *a'*, the inside of which strip *m* is chamfered or bevelled, making a recess, *n'*, between said strip and frame. Screws *a a* may then be inserted in the frame, passing through the channel *n* or recess *n'*.

The springs *b b*, which may be made of flat steel, and having a notch, *c*, in each end, and suitably tempered, are then inserted in the channels *n n*, as shown in fig. 2, and are so placed that the screws *a a* pass through the notches *c* in the ends of said springs *b*, thus keeping said springs in their proper position, while the springs themselves may have their bearing either against the bottom of the channels *n n*, or against the screws *a a*.

The strip of webbing, *f*, or other material, and of any desirable width, may be placed between the springs and the frame A, and secured at each end of the seat-back, at *h*, or elsewhere, for the purpose of preventing the springs from pressing through or bending the other way; although, as the seat is covered with some strong material, upon the back side, there is no real necessity for using said strip of webbing in most cases.

Suitable duck or other stout material is then placed over the convex side of the springs, and tacked, or otherwise secured around the edge of the frame at *d*, and the outer covering, *s*, is placed over this, and likewise secured at *d*, the space between meanwhile being stuffed with hair, or other suitable material.

The covering and stuffing, however, are not a part of my invention, as they have, of course, long been used.

The back may then be covered with suitable material, or may have any desirable wood-finish, the strip or piece *f* being used when the body or frame A is made open.

The construction is shown in the drawings as applicable more particularly to car-seat backs, although it is, of course, applicable to any seat back.

Its operation is as follows:

The springs, cloth, and stuffing being in place, as shown in fig. 2, if a person reclines against the back at *x*, that particular part with which the person comes in contact yields to the pressure, while the part above is forced outward; and if a set of these springs be used, and a person lean against the convex part of the set, that part of the back which is forced outward adapts itself to the body of the person using it, making a much more comfortable and easy back than is possible by any other known means.

By this arrangement, much less hair or stuffing-material is required, and more labor and expense saved than in the construction of seat-backs now practised.

It is evident that a metallic strip, properly chamfered, or having a longitudinal channel, *n*, therein, might be properly secured to the wood portion of the seat-back, said strip having suitable protuberances in its channel as an equivalent to the screws *a a*, this device being merely an equivalent to my invention.

I am aware that various seats or cushions have been constructed, having flexible metallic springs, but they have generally been made upon an entirely different

principle, as shown in Letters Patent granted to L. W. Fillebrown, Jr., dated July 10, 1866, and numbered 56,200, in which more or less of the whole convex surface of the springs is forced downward or inward, when acted upon, no part of said springs being forced outward to adapt themselves to the body of the user; and, indeed, it would not be desirable, in a seat or cushion, to have any portion operate in an outward direction, and conform to the body, as a great desideratum in a cushion is that it may be cool and agreeable, while the pressure against a seat-back is not sufficient to cause heat in any great or undesirable degree.

I disclaim, therefore, said device, for which Letters Patent were granted to said Fillebrown, or any part

of it, and all other devices, irrespective of my own particular arrangement and construction; but having described my invention,

What I do claim as new, and desire to secure by Letters Patent, is—

The metallic springs *b b*, attached to the body or frame *A*, the ends of said springs having a bearing in the channels *n* or *n'*, with the screws *a a* or other protuberances therein, the whole, when covered and stuffed, forming a seat-back, all constructed and operating substantially as herein described and set forth.
